CALENDER ROLL

LeRoy Eaby, Providence Township, Lancaster County, Pa., assignor to Armstrong Cork Company, Lancaster, Pa., a corporation of Pennsylvania

Application December 15, 1953, Serial No. 398,353

7 Claims. (Cl. 257—95)

In the operation of sheeting calenders such as those currently used in the manufacture of floor and wall coverings, it is highly desirable to control the temperature on the surface of the roll within a very limited range in order to produce sheet material having the desired surface characteristics and the desired design effects.

One type of roll used for this purpose in calendering thermo-plastic materials is disclosed in United States Patent No. 2,498,662, issued February 28, 1950. The roll disclosed in this patent has a relatively thin outer shell provided with a plurality of annular channels disposed immediately beneath the working surface of the roll. The purpose of this arrangement of annular channels is to provide a system in which the temperature control fluid acts immediately on the working surface of the roll and prevents the entrapment of a large quantity of fluid in the center of the roll where it is ineffective for controlling the temperature of the working surface of the roll.

The present invention relates to a mechanism for changing the amount of temperature control fluid directed to different areas of the roll surface in accordance with specific requirements. With the system of this invention, it is possible to maintain certain areas of the roll at temperatures different from the temperatures in other areas of the roll. For example, if desired, the ends of the roll may be operated at a different temperature from the intermediate section of the roll. Also, in instances where certain areas of the roll are subject to greater temperature fluctuation due to increased heat transmission, etc., it is possible to offset this fluctuation by directing a greater amount of heat control fluid through the heat control fluid passages in these areas. The system is, therefore, effective to maintain certain areas of the roll surface at different temperatures where the normal temperature of the roll surface is constant; or it may be used to maintain a constant temperature at all points on the roll surface when the normal temperature of the roll surface is not constant.

For example, in the calendering of asphalt tile, cold brine is circulated through the top or facing roll of the calender to keep the roll surface from getting too hot. However, if the rate of flow of brine is the same throughout the entire roll, the ends of the roll become too cold, with the result that the edges of the calendered sheet have different surface characteristics than the remainder of the sheet. To overcome this trouble caused by cold ends on the rolls, the device hereinafter disclosed has been utilized.

The system is suitable for the transfer of heating fluid or cooling fluid through the roll, depending on the specific requirements of the product being formed into a sheet on the calender in which the roll is a component part.

In the system here under consideration, it is possible to transmit temperature control fluid at different temperatures to different areas of the roll. This is done by dividing the working area of the roll into zones and having

2

a separate injector to supply fluid to each of these zones. The temperature can be controlled either by adjusting the valves supplying fluid to different zones or by supplying the same quantity of fluid but at a different temperature.

An object of this invention is to provide a system whereby it is possible to control the temperature of the surface of a calender roll by controlling the distribution of temperature control fluid within the body of the roll.

Another object of this invention is to provide a calender roll in which the rate of flow of temperature control fluid supplied to different areas of the roll can be controlled to vary the temperature at different areas of the roll at any given time.

In order that this invention may be more readily understood, it will be described in connection with the attached drawings, in which:

Figure 1 is a longitudinal cross sectional view of a calender roll with the injector mechanism attached thereto;

Figure 2 is a longitudinal cross sectional view of a calender roll taken on the line 2—2 of Figure 4 showing the internal passages for the introduction of temperature control fluid to the annular passages adjacent the surface of the roll;

Figure 3 is a cross sectional view taken on the line 3—3 of Figure 1;

Figure 4 is a cross sectional view taken on the line 4—4 of Figure 2;

Figures 5 and 6 are cross sectional views similar to Figures 1 and 2 but show a modification of the invention; and

Figure 7 is a view of a modification.

Referring to Figure 1, there is shown a calender roll 2 having a relatively thin outer shell 3 provided with a plurality of annular channels 4 formed on the inner surface thereof. This outer shell 3 surrounds a central core 5 having a longitudinal central passage 6 carrying a plurality of concentric pipes. These pipes conduct the fluid into the central part of the roll and remove it from the roll after it has circulated through the channels 4 adjacent the working surface of the roll.

Referring to Figure 2, it will be seen that the cavity 6 forms a passage surrounding outer concentric pipe 7. This passage serves as the conduit for injecting the temperature control fluid into the roll in the preferred embodiment of the invention.

Referring to Figure 1, it will be seen that supply pipe 8 from a source not shown leads into a circular manifold 9 surrounding the end of the roll. It will be understood that the injector system shown at the left-hand end of Figure 1, designated generally by the numeral 10, is stationary, while the roll 2 rotates with respect thereto. The collar 11 is secured to the neck of the roll 2 by means of studs 12. This collar 11 forms a continuation of the passage 6 between the outer concentric pipe 7 and the roll core 5. This passage is in communication with circular manifold 9 and, therefore, fluid injected into circular manifold 9 from supply pipe 8 will flow through the passage between the outer concentric pipe 7 and the roll core 5 into the central part of the roll, where it is conducted through radial passages 13 located close to the center of the roll.

Referring now to Figure 2, it will be seen that there are two sets of radial passages 13 disposed at 180° with respect to one another. Each set of radial passages 13 communicates with a horizontal inlet manifold 14 located on the outer circumference of the core 5. These horizontal inlet manifolds 14 are isolated from the annular channels 4 by means of shields 15. These shields 15 are provided with apertures 16 communicating with the annular channels 4. It will be seen that the horizontal

inlet manifold 14 at the bottom of Figure 2 communicates with the first annular channel and also with alternate annular channels along the length of the roll. It will also be seen that the horizontal inlet manifold 14 at the top of the roll communicates with the second annular channel and alternate channels throughout the roll.

Referring now to Figure 4, it will be seen that as the fluid enters the annular channels 4 from the horizontal inlet manifold 14 it can flow around the annular channel 4 in either direction until the two streams meet at a point approximately 180° with respect to the point of entrance. At this point there is an aperture 17 leading from the annular channel 4 to a discharge manifold 18. The arrangement of discharge manifolds is the same as the arrangement of the inlet manifolds except that they are angularly displaced from one another a slight amount on the circumference of the roll.

Referring now to Figure 1, there is shown the system for exhausting or discharging the temperature control fluid from the annular channels 4. This system comprises a system of exhaust manifolds 18 sealed from the annular channels 4 by shield 19 provided with apertures 17. It will be seen that the fluid is discharged through aperture 17 from the first annular channel 4 into exhaust manifold 18 positioned along the top of the roll, and the second annular channel discharges into exhaust manifold 18 at the bottom of the roll. Each of these exhaust manifolds 18 is divided into three compartments by means of dams 18—the two end compartments 20 and the central compartment 21. Each of these sets of compartments is connected to a separate discharge pipe in the concentric pipe system passing through the central cavity of the roll. Starting at the right end of Figure 1, it will be seen that the exhaust fluid discharged into compartments 20 from the first four annular channels will pass through a radial passage 22 into the inner concentric pipe 23. This inner concentric pipe runs through the center of the roll to the extreme left end of the injector 10, where it discharges into a radial manifold 24, which in turn discharges into pipe 25, the flow through which is controlled by means of valve 26. The fluid from the four annular channels at the left end of the roll is discharged into compartments 20 at the left end of the roll through radial passages 27 into the intermediate concentric pipe 28, which discharges into radial manifold 29 in the injector system 10. Radial manifold 29 discharges through pipe 30 and the flow is controlled by valve 31.

The two large compartments 21 taking the exhaust fluid from the remaining channels in the roll communicate to the outer concentric pipe 32 through radial passages 33 leading from each compartment 21. The fluid from the outer concentric pipe 32 leads to radial manifold 34 which discharges through pipe 35 controlled by valve 36. It will be understood that each pipe in the concentric system is sealed from the other systems so that fluid cannot lead from one to the other. This is accomplished by the packing glands 37, 38, 39, and 40 located adjacent each manifold. The radial discharge passages 22, 27, and 33 are in the form of threaded pipe which is threaded through the core 2 into a threaded nipple on the pipe to which they are connected to prevent leakage at the point where the pipe system and core abut.

In the operation of the device, temperature control fluid of the proper temperature is conducted into the roll through pipe 8. The rate of flow is controlled by valve 41. The fluid enters radial manifold 9 and flows into the central cavity of the roll between the roll core and outer concentric pipe 32. From this cavity the fluid flows through radial passages 13 into radial inlet manifold 14 through apertures 16 in the shield 15 into the annular channels 4 positioned between the core 5 and the shell 3 of the roll. If it is found that the ends of the roll are too cold by reason of the temperature control fluid removing too much heat from that area, the amount of fluid leaving the end channels can be controlled by means

of valves 26 and 31, valve 26 controlling the flow of fluid from the four channels at the right end of the roll and valve 31 controlling the flow of fluid from the channels at the left-hand end of the roll. With this system, it is possible to accurately control the temperature, inasmuch as flow can be completely stopped in the channels or impeded to any extent necessary.

Should it be found desirable to run fluid through different zones of the roll at different temperatures, this can be accomplished by utilizing the modification illustrated in Figures 5 and 6, in which it will be noted that the concentric pipes are arranged in a different manner. Also in this embodiment both the inlet manifolds and the exhaust manifolds are divided into compartments by means of dams. Referring to Figure 5, it will be seen that the inner pipe 42 extends the full length of the roll cavity and is connected to compartments 20 at each end of the roll by means of radial passages 22 at the right-hand end of the roll and radial passages 27 at the left-hand end of the roll. Central pipe 42 in this modification is connected to the end manifold 24 the same as central pipe 23 is connected thereto in the other embodiment earlier described.

Referring now to Figure 6, it will be seen that the intermediate concentric pipe 43 communicates with the end manifold compartments 44 through radial passages 45 on the right-hand end of the roll and radial passages 46 on the left-hand end of the roll. This intermediate pipe is in communication with radial manifold 29 in the same manner as earlier described. With this arrangement, temperature control fluid can be introduced into the end channels of the roll from supply pipe 30, emptying into radial manifold 29, from which the fluid is conducted through intermediate pipe 43, radial passages 45 and 46, to the end compartments 44 in the inlet manifold 14. After the fluid has made one pass through the annular channels 4, it empties into end compartments 20 of the exhaust manifold, flows through radial passages 22 and 27 into the inner concentric pipe 42, which carries it to radial manifold 24 from which it is discharged through pipe 25. The radial flow of supply and the exhaust can both be controlled by means of valves 26 and 31. Should it be found desirable for some reason, the temperature control fluid can be conducted into the roll through pipe 25 and inner pipe 42 and exhausted through the intermediate pipe 43 into radial manifold 29. The remainder of the roll can, if desired, be controlled by temperature control fluid of a different temperature, entering the roll from pipe 35 into circular manifold 34, which communicates with outer concentric pipe 47. The fluid entering the roll in outer pipe 47 is forced through radial passages 48 into the manifold compartment 49. After it has passed through the annular channels, it is discharged through radial passages 33, which in this embodiment lead into the passage 6 between the roll core and the outer pipe 47. The fluid is conducted through passage 6 to radial manifold 9, which discharges the fluid into pipe 8. In this arrangement, the control of fluid entering and leaving the roll may be controlled by valves 36 and 41. Should it be found desirable, the direction of flow may be reversed and the fluid may be supplied to the roll through the outer passage 6 and discharged through the outer pipe 47. With this embodiment, it is possible to regulate the temperature at the ends of the roll by introducing temperature control fluid at a higher temperature or decreasing the volume of fluid or by adjusting both the temperature and the volume.

Should it be found desirable to vary the number of annular channels at the end of each roll through which fluid of a higher temperature is conducted or in which fluid is entrapped, this can be accomplished by increasing or decreasing the size of the end manifold compartments 20 and 44. It has been found that an adjustable dam 50 can be used to accomplish this purpose. In the embodiment illustrated in the Figures 1 to 6, the end compartments supply fluid to four annular channels; however,

as conditions vary, it may be found desirable to limit the number of channels supplied from the end compartments or increase the number. With the adjustable dam shown in Figure 7, this may be varied anywhere from one channel to six channels. This is done by means of a screw 51, the thread of which engages a thread in the dam 50. The head of the screw is accessible by removing the plug 52 in the end of the roll. It will be understood, of course, that Figure 7 shows only one dam and one compartment 44; however, it will be understood that all dams controlling the size of each end compartment would be similarly equipped.

It will be seen that this invention provides a system which is fairly flexible in that the volume of temperature control fluid which flows through different zones in the roll can be accurately controlled by valves located exteriorly of the roll, or fluid of a different temperature can be directed to different zones to control the surface temperature of the roll.

I claim:

1. In a heat exchange roll of the shell type, comprising an outer shell and an inner core with a temperature control fluid circulating system disposed therebetween for controlling the temperature of the roll surface, means for dividing the temperature control fluid circulating system into zones along the length of the roll, said inner core being provided with a longitudinal central cavity, means for supplying temperature control fluid into said central cavity and means for discharging temperature control fluid from said central cavity, means connecting said supply means and said discharge means with the individual zones of the temperature control fluid circulating system, and separate control means to control the volume of fluid flowing through one zone separately from the fluid flowing through an adjacent zone.

2. In a heat exchange roll of the shell type, comprising an outer shell and an inner core with a temperature control fluid circulating system disposed therebetween for circulating temperature control fluid to control the temperature of the roll surface, means for dividing the temperature control fluid circulating system into a plurality of zones along the length of the roll, a separate supply system for supplying temperature control fluid to the end zones in the roll, a separate discharge system for discharging temperature control fluid from the end zones, a separate means for conducting temperature control fluid to the remainder of the circulating system, and a discharge means for discharging the temperature control fluid from the remainder of the system.

3. In a heat exchange roll of the shell type, comprising an outer shell and an inner core with a temperature control fluid circulating system disposed therebetween for circulating fluid to control the temperature of the roll surface, means for dividing the temperature control fluid circulating system into zones, means for adjusting the size of said zones, and means for conducting heat transfer fluid to said zones and exhausting heat transfer fluid from said zones.

4. In a heat exchange roll of the shell type, comprising an outer shell and an inner core with a temperature control fluid circulating system disposed therebetween for circulating temperature control fluid to control the temperature of the roll surface, means for dividing the tem-

perature control fluid circulating system into zones along the length of the roll, means for conducting temperature control fluid into all of said zones, means for discharging temperature control fluid from the individual zones, and adjusting means located externally of the roll to vary the volume of temperature control fluid directed through one zone from that directed through other zones.

5. In a heat exchange roll of the shell type, comprising an outer shell and an inner core with a temperature control fluid circulating system disposed therebetween for controlling the temperature of the roll surface, means for dividing the temperature control fluid circulating system into zones along the length of the roll, said inner core being provided with a longitudinal central cavity, means for supplying temperature control fluid into said central cavity and means for discharging temperature control fluid from said central cavity, means connecting said supply means and said discharge means with the individual zones of the temperature control fluid circulating system, and separate control means located externally of the roll for varying the volume of the temperature control fluid circulating through one zone from that flowing through the adjacent zone.

6. In a heat exchange roll of the shell type, comprising an outer shell and an inner core with a temperature control fluid circulating system disposed therebetween for controlling the temperature of the roll surface, means for dividing the temperature control fluid circulating system into zones along the length of the roll, said inner core being provided with a longitudinal central cavity, means for supplying temperature control fluid into said central cavity and means for discharging temperature control fluid from said central cavity, means connecting said supply means and said discharge means with the individual zones of the temperature control fluid circulating system, and means located externally of the roll for separately controlling the temperature control fluid supplied to each zone.

7. In a heat exchange roll of the shell type, comprising an outer shell and an inner core with a temperature control fluid circulating system disposed therebetween for controlling the temperature of the roll surface, means for dividing the temperature control fluid circulating system into zones along the length of the roll, said inner core being provided with a longitudinal central cavity, means for supplying temperature control fluid into said central cavity and means for discharging temperature control fluid from said central cavity, means connecting said supply means and said discharge means with the individual zones of the temperature control fluid circulating system, and separate means located externally of the roll for separately controlling the temperature control fluid discharged from each of said zones.
